UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

STOP-MOTION FOR CIRCULAR-KNITTING MACHINES.

1,078,678.

Specification of Letters Patent.

Patented Nov. 18, 1913.

Original application filed May 17, 1912, Serial No. 697,861. Divided and this application filed October 29, 1912. Serial No. 728,363.

To all whom it may concern:

Be it known that I, HARRY A. HOUSEMAN, a citizen of the United States, residing at Philadelphia, county of Philadelphia, and State of Pennsylvania, have invented a new and useful Improvement in Stop-Motions for Circular-Knitting Machines, of which the following is a full, clear, and exact description, reference being had to the accompanying drawings, which form a part of this specification.

The object of my invention is to so construct the driving connections to the cam cylinder or other rotatable member or members of a circular knitting machine that the machine will automatically stop in the event of any obstruction to rotation of the cam cylinder.

The invention comprises the means described hereinafter and illustrated in the accompanying drawings, in which—

Figure 1 is a front elevation of the knitting machine with certain of the parts having no direct relation to the invention removed; Fig. 2 is a sectional plan on the line 2—2 of Fig. 1; Fig. 3 is an enlarged vertical section of the machine; Fig. 4 is a partial section on the line 4—4 of Fig. 3; Fig. 5 is a section on the line 5—5 of Fig. 1, showing the belt shifting mechanism.

a is the frame of the machine and b the upper bed plate. Projecting upward from the bed plate b is a spider c on which rests the non-rotatable needle cylinder d. The needle cylinder d has slots e extending from the inner periphery outward. These slots contain the needles f which are operated from needle levers g pivoted on the comb h. The comb h rests on the bed plate b. The rotatable cam cylinder i is located within the needle cylinder d.

Resting on the needle cylinder d is the sinker head k having the cap j having cams adapted to actuate the sinkers or web-holders l.

The cam cylinder i and the sinker cap j are rotated and oscillated together. The cam cylinder at its lower part has on its outer face a gear 11 engaging the outer gear 13 of a ring 12. The ring 12 carries also an inner gear 14 which engages a pinion 15 on the shaft 16. The shaft 16 also carries a pinion 17 which engages a gear 18

on the sinker head k. The ring 12 is the driving element of the chain of gearing described. As shown, the ratio between gears 11 and 13 is one to one, between pinion 15 and gear 14 one to two, and between gear 17 and gear 18 one to two, and the cam cylinder and sinker head therefore have imparted to them precisely similar movements, as if they were rigidly secured together.

The ring 12, from which both the cam cylinder i and sinker cap j derive their movements as above described, is driven from the clutch-shaft 20 by means to be herein-after described. On the clutch shaft 20 are slidably mounted the two pinions 21 and 22, which are adapted to be moved up or down in unison by means not herein set forth, as the same forms no part of this invention. The clutch 23 is fixed on the shaft 20, between pinions 21 and 22. The upper pinion 21 is constantly rotated and the lower pinion 22 constantly oscillated. When the pinions 21 and 22 are moved down, thus engaging the rotary pinion 21 with the clutch 23 and disengaging the oscillatory pinion 22, the ring 12 is continuously rotated, thus rotating the cam cylinder i and sinker cap j. When the pinions 21 and 22 are elevated, thus disengaging the rotary pinion 21 from the clutch 23 and engaging the oscillatory pinion 22, the ring 12 is constantly oscillated, thus oscillating the cam cylinder i and sinker cap j. The pinion 21 is constantly rotated by means of a spur gear 25 meshing with the pinion 21. The shaft 26 of the spur gear 25 also carries a bevel gear 27 driven from a bevel pinion 28 on the driving shaft t. The pinion 22 is constantly oscillated by the following means: On the shaft 26 is a crank 29 connected by a link 30 with an arm 31 turning on a post 32. Extending from the hub of the arm 31 is a quadrant 33 engaging the pinion 22.

The ring 12 is of substantially greater thickness than the gears 13 and 14 carried by it. The part of the ring 12 projecting below the gears 13 and 14 rotates in a cup-shaped casing 35 through which the upper end of the clutch shaft 20 projects. The clutch shaft 20 has secured to it spider 36. A latch 37 extends from the axis of the shaft 20 through one arm of the spider 36 into a beveled recess in the inner face of the

ring 12. The outer end of the latch 37 is correspondingly beveled and is held in the recess by means of a spring 38. The inner end of the latch is beveled and engages the 5 beveled upper end of a rod 39 extending axially through the clutch shaft 20. It will thus be seen that the drive between the clutch shaft 20 and the ring 12 is not a positive one. So long, however, as there is no 10 obstruction in the knitting mechanism tending to stop the operation of the cam cylinder *i* or sinker cap *j*, these members are driven from the clutch shaft 20 as if the ring 12 were positively secured thereto; but 15 in the event of any obstruction to the operation of the cam cylinder *i* or sinker cap *j* the latch 37 will be forced inward, thus destroying the driving connection between the shaft 20 and the ring 12. At the same time 20 the rod 39 will be depressed, and the machine stopped by means which I shall now describe (see Figs. 1 and 5).

On the driving shaft *t* are the fixed driving pulley 40 and the loose idle pulley 41. 25 42 is a belt-shifter secured to the slideable shaft 43. A spring 44 tends to move the shaft 43 into position to cause the belt shifter 42 to move the belt into engagement with the loose pulley 41. By means of a 30 hand lever 45 engaging a collar 46 on the shaft 43, the shaft 43 and belt-shifter 42 may be moved into position to bring the belt into engagement with the driving pulley 40, the shaft 43 being retained in this 35 position by means of a latch 48 (on the collar 46) dropping back of a lug 49 on a bell-crank lever 50. The lower end of the rod 39 rests upon one end of an intermediately pivoted lever 51, the other end of the lever 40 51 extending under and between the ends of, a lever 52. The lever 52 is pivoted at one end and its other end is hooked over one end of a lever 53, the other end of lever 53 engaging one arm of the bell-crank lever 45 50. When the rod 39 is depressed, as above described, it rocks the lever 51, and the lever 51 in turn rocks the lever 52, the hooked end of the latter thereby being withdrawn from engagement with the lever 53. The 50 latter is thus released, and under the influence of a spring 54, moves the bell-crank lever 50 into position to cause the lug 49 to recede from the latch 48, whereupon the spring 44 moves the belt-shifter 42 into position to shift the belt from the driving pulley 40 to the loose pulley 41, thereby stopping the machine.

The mechanism for vertically moving the clutch 23 is not illustrated, as the same 60 forms no part of my invention.

The subject matter of this application is divided out of an application filed by me May 17, 1912, Serial No. 697,861, in which said subject matter is shown and described 65 but not claimed.

Having now fully described my invention, what I claim and desire to protect by Letters Patent is:

1. In a circular knitting machine, the combination with a rotatable cylinder, of a driving shaft, a driven shaft, driving connections between the two shafts, mechanism to stop the rotation of the driving shaft, a rod extending axially within the driven shaft, connections between the rod and the stop mechanism, and normally operative yielding driving connections between the driven shaft and the rotatable cylinder adapted to be retracted and rendered inoperative by resistance to rotation of the cylinder and effect 80 a longitudinal movement of said rod. 70

2. In a circular knitting machine, the combination with a rotatable cylinder, of a rotatable member in driving engagement with the cylinder, a driven shaft on the axis 85 of the rotatable member, a driving shaft, driving connections between the two shafts, mechanism to stop the rotation of the driving shaft, normally operative driving connections between the driven shaft and said 90 rotatable member adapted to be rendered inoperative to drive by resistance to rotation of the cylinder and said rotatable member, and normally inoperative means carried by the driven shaft and adapted to actuate the stop-mechanism and to be operated by said yielding driving connections when the latter are rendered inoperative to 95 drive.

3. In a circular knitting machine, the 100 combination with a rotatable cylinder and a gear carried thereby, of a gear in driving engagement with the first gear, a driven shaft, a spider carried by the shaft, means carried by the spider in yielding driving 105 engagement with the second gear, a driving shaft, driving connections between the two shafts, mechanism to stop the rotation of the driving shaft, means holding said stop mechanism from action and normally engaging 110 said yielding driving means but adapted, when the yielding driving means is actuated by resistance to rotation of the gears, to be operated by the yielding driving means to dictate the operation of said 115 stop mechanism.

4. In a circular knitting machine, the combination with a rotatable cylinder, of a driving shaft, a driven shaft, driving connections between the two shafts, mechanism 120 to stop the rotation of the driving shaft, normally operative driving connections between the driven shaft and the rotatable cylinder including a spring-pressed latch adapted to be retracted and thus rendered 12 inoperative to drive by resistance to rotation of the cylinder, a rod carried by the driven shaft and having a beveled face in constant engagement with a beveled face on said latch whereby upon the retraction 121

- of said latch the rod will be moved longitudinally, and connections between said rod and the stop mechanism adapted to render the latter operative in the said actuation of 5 said rod.
5. In a circular knitting machine, the combination with a rotatable cylinder, of a rotatable member in driving engagement with the cylinder, a driven shaft on the axis 10 of the rotatable member, a driving shaft, driving connections between the two shafts, mechanism to stop the rotation of the driving shaft, a rod extending axially within the driven shaft, and a spring pressed latch 15 having beveled faces engaging respectively a beveled driving face on said rotatable member and a beveled driving face on the rod whereby said latch will be retracted and actuate said rod under given resistance to 20 rotation of said rotatable member, and connections between said rod and the stop mechanism adapted to render the latter operative in the said actuation of said rod.
6. In a circular knitting machine, the combination with a rotatable cylinder, of a rotatable member in driving engagement with the cylinder, a driven shaft on the axis 25 of the rotatable member, a driving shaft, driving connections between the two shafts, mechanism to stop the rotation of the driving shaft, a rod, a spring-pressed latch 30 having beveled faces engaging respectively a beveled driving face on said rotatable member and a beveled driving face on said 35 rod, whereby, under given resistance to rotation of said rotatable member, said latch will be retracted and actuate said rod in a longitudinal direction, and connections between said rod and the stop mechanism 40 adapted to render the latter operative in the said actuation of said rod.
7. In a circular knitting machine, the combination with a rotatable cylinder, of a 45 rotatable ring the upper part of which is in driving engagement with the cylinder, a driven shaft on the axis of the ring, a cup-shaped casing in which the lower part of the ring rotates and through which said shaft projects, a rod extending axially within 50 said shaft and through said casing, a latch within the casing and extending between and yieldingly engaging said ring and rod whereby the latch will be actuated to 55 actuate said rod under given resistance to rotation of said cylinder and ring, a driving shaft, driving connections therefrom to the driven shaft, mechanism to stop the rotation of the driving shaft, and connections between said rod and stop mechanism adapted to render the latter operative in the ac- 60 tuation of said rod.
8. In a circular knitting machine, the combination with a rotatable cylinder and a rotatable sinker head, of a driving shaft, a driven shaft, driving connections between 65 the two shafts, mechanism to stop the rotation of the driving shaft, normally operative yielding driving connections between the driven shaft and the rotatable cylinder and sinker head adapted to be rendered in- 70 operative to drive by resistance to rotation of the cylinder or sinker head, and means holding said stop mechanism from action and normally engaging said yielding driving connections but adapted, when said 75 yielding driving connections are so rendered inoperative to drive, to be operated by the yielding driving connections to dictate the operation of said stop mechanism.

In testimony of which invention, I have 80 hereunto set my hand, at Phila., on this 25th day of October, 1912.

HARRY A. HOUSEMAN.
